UNITED STATES PATENT OFFICE

CHARLES L. MCCUEN, OF LANSING, MICHIGAN, ASSIGNOR TO GENERAL MOTORS CORPORATION, OF DETROIT, MICHIGAN, A CORPORATION OF DELAWARE

METERING MEANS FOR OIL FILTERS

Application filed December 7, 1927. Serial No. 238,411.

This invention relates to internal combustion engines, and particularly to the lubrication thereof. The invention is particularly concerned with internal combustion engines as used on automotive vehicles.

In prior constructions a portion of the oil delivered by the usual pump used in force feed lubrication systems has been sent to the filter and returned therefrom either directly to the crankcase or to a working part of the engine. The portion of the oil sent into the filter has usually been by-passed by means of a suitable by-pass means, and the present invention is particularly concerned with an arrangement for metering a portion of the oil to the usual oil filter.

My novel dispensing or metering arrangement is built in the camshaft and comprises a plurality of openings or passages through the camshaft at one of the bearings. The oil is delivered to these passages from a second inclined passageway which leads from a groove around the camshaft. The oil to this groove is delivered through a duct constructed in a rib of the crankcase and leading from a crankshaft bearing.

Leading through a rib of the crankcase to the outside thereof is a duct, the inner end of which is adapted to register intermittently with the passages through the camshaft as it rotates. The force feed lubrication system will force the oil past the crank shaft bearing to the groove in the camshaft from where a portion of the oil will pass through the inclined or diagonal passage into the transverse passages of the cam shaft, and as the cam shaft rotates the opening will intermittently register with the duct in the crankcase rib and thereby cause a shot of oil to pass through the duct each time the camshaft opening registers with the duct.

Outside of the crankcase there is connected to the duct outlet a connection leading to the conventional oil filter. The oil filter head is secured to the crankcase prefer-

ably at the breather opening and has an outlet to lead the oil back through the crankcase into the usual oil pan. I may so construct the filter head as to adapt it to fit and be secured to a portion of the crankcase, the head thereby serving as a means for supporting the filter.

If desired, the conventional type of filter may be used and a lead pipe provided from the filter to the crankcase, no special head being necessary.

The invention is disclosed on the accompanying drawings in which:

Figure 1 is a view of an internal combustion engine, with parts broken away and shown in section, showing the application of my invention.

Figure 2 is a section on line 2-2 of Figure 1 looking in the direction of the arrows.

Figure 3 is a detailed view of the groove and oil passageways in the cam shaft at one of the bearings.

Figure 4 is a view similar to Figure 2 of a modification.

Referring to the numbered parts on the drawings, 10 indicates an internal combustion engine as a whole, 12 the crankcase, 14 the oil pan, 16 the crankshaft, and 18 the cam shaft. The crankshaft has four bearings shown at 20, 22, 24 and 26, and to each of these bearings there leads an arm 28 from an oil manifold 30, to which oil is delivered from the oil pump shown at 32.

My invention is applied to one of the bearings of the camshaft, preferably the bearing shown at 34 which is a second bearing from the rear of the engine, although any other bearing would do just as well. The specific construction of the metering arrangement of the camshaft at this bearing is better shown in Figure 3. The camshaft is provided with a peripheral groove 36 which receives oil from the passageway 38 leading from the bearing 24 of the crankshaft. All the crankshaft bearings are similar the oil passing

the bearings through the groove 40 in each bushing member 42. If desired, the groove 36 may be placed in the bushing 35 instead of the camshaft. Leading from the groove 36 is a diagonal or an inclined passage 44 which conducts the oil to a pair of transverse passages 46 and 48 passing through the cam-shaft 18 at right angles to each other. The passageway 44 from the groove 36 preferably delivers the oil at the meeting point of the two passageways 46 and 48. While I have shown two passageways 46 and 48 at the bearing 34, it will be understood that I may use one or more as desired, however, in practice two are preferred.

Constructed in a rib 50 of the crankcase is a duct 52 leading from the bearing 34 to a point 54 outside the crankcase. This duct 52 is so placed so that it will register with the ends of the passageways 46 and 48 through the intermediary of the opening 47 in the bushing 35. As the cam shaft rotates and the ends of the passageways 46 and 48 register intermittently with the duct 52, the force feed lubrication system will cause a shot of oil to flow through the passageways 46 or 48 and to enter the duct 52. Connected at the point 54 to the duct 52 is a pipe 56 which leads to an inlet 58 of an oil filter 60 secured to the crankcase 12.

In Figures 1 and 2 the invention is shown in its preferred form and is applied at the crankcase breather and oil supply opening. In these figures the filter head 76 has a special construction as shown so that it may be secured to the specially constructed flat portion 80 formed on the crankcase. With this construction, I eliminate the filter outlet pipe 64 shown in Figure 4 and allow the filtered oil to pass directly from the filter through the outlet passage 78 into the opening 82 in the crankcase and on to the oil pan 14. The oil filter opening is shown at 84, and the crankcase at this point has a special construction, as shown in Figure 2. Suitable piping 56; shaped in any suitable way to avoid obstructing the breather opening 84, leads from the duct 52 to the entrance 58 of the oil filter. The oil filter head 76 is shown as attached to the crankcase by means of a bolt 88 passing therethrough and threaded into the crankcase, as shown at 90. The filter head and its arrangement with the crankcase is covered in my application Serial No. 265,259, filed March 28, 1928, and which has eventuated into Patent #1,788,884.

In Figure 4, I have shown a modification in the adaptation of the filter to the oil metering system. The construction at the crank and cam shaft is identically the same as shown and described in Figures 1, 2 and 3. The outlet 62 of the filter has applied thereto a pipe 64 which leads to an inlet 66 located at the bottom of the crankcase between two stiffening flanges 68 and 70 which are pref-

erably provided with strengthening ribs 71 along their length. The crankcase at this point has preferably a special construction as shown at 72 to form a passageway by which the oil may be returned to the oil pan 14. If desired, this special construction 72 may be omitted and the oil allowed to flow directly through the side of the crankcase into the oil pan. Additional reinforcing flanges 86 are provided inside the crankcase parallel to the flanges 68 and 70.

The operation of the oil metering means is as follows: The pump 32 will force the oil to the manifold 30 through the lead 28 to the bearing 24. The oil will lubricate the bearing 24 and the excess pass through the groove 40 of the bushing 42 and passage 38 to the groove 36 in the cam shaft and lubricate the bearing 34. The excess oil will flow from the groove 36 through the diagonal passage 34 to the crossing point of the passages 46 and 48 from where it will be delivered to the duct 52 each time the ends of the passageways 46 or 48 conform to the duct in the rib 50. A shot of lubricant will accordingly be delivered to the duct 52 four times for each rotation of the camshaft, and these shots of oil will be delivered through the pipe 56 to the filter 60 and the oil after passing through the filter will be returned to the oil pan 14 through the openings 78 and 82 or the pipe 64 and passage 74.

The operation of the species shown in Figure 4 is in all respects similar to that shown in Figures 1 and 2.

While I have shown the metering arrangement for my new system of lubrication as applied to but one of the bearings of the cam-shaft, it will be readily understood that a similar metering arrangement may be applied to two or more of the bearings.

I claim:

1. In an oiling system as applied to internal combustion engines, an oil filter, means for supplying oil under pressure to the bearing parts of the engine, a movable part of said engine constructed to serve and operate as an oil dispensing means, and means for passing said dispensed oil to the filter.

2. In an oiling system as applied to internal combustion engines, an oil filter, means for supplying oil under pressure to the bearing parts of the engine, a camshaft, means associated with said camshaft constructed to serve and operate as an oil dispensing means, and means for returning said dispensed oil to the oiling system through the filter.

3. In an oiling system as applied to internal combustion engines, an oil filter, means for supplying oil to the bearing parts of the engine, a camshaft, a passage in the camshaft serving as an oil dispensing means, and means for returning said dispensed oil to the oiling system through the oil filter.

4. In an oiling system as applied to inter-

5 internal combustion engines, an oil filter, means for supplying oil to the bearing parts of the engine, a camshaft, a plurality of passages in the camshaft serving as an oil dispensing means, and means for returning said dispensed oil to the oiling system through the oil filter.

10 5. In an oiling system as applied to internal combustion engines, an oil filter, means for supplying oil to the bearing parts of the engine, a camshaft, oil dispensing means in the camshaft at a camshaft bearing, and means for returning the oil to the oiling system through the oil filter.

15 6. In a lubricating system for internal combustion engines, a cam shaft operating in bearings, a pump for supplying oil under pressure to the bearing parts of the engine, a plurality of passages at a cam shaft bearing for dispensing the oil delivered to said bearing, a duct leading from the bearing for conducting away the dispensed oil, and an oil filter for receiving the oil from the duct.

20 7. In an oiling system as applied to internal combustion engines, an oil filter, means for supplying oil under pressure to the bearing parts of the engine, a camshaft operated from said engine and constructed to serve as an oil dispensing means, and means for passing said dispensed oil to the filter.

25 8. In an oiling system as applied to internal combustion engines, an oil filter, means for supplying oil under pressure to the bearing parts of the engine, a movable member operated from said engine and constructed to serve as an oil dispensing means, said dispensing means including a passage in the movable member, and means for passing said dispensed oil to the filter.

30 9. In an oiling system as applied to internal combustion engines, an oil filter, means for supplying oil under pressure to the bearing parts of the engine, a movable member operated from said engine, oil dispensing means comprising a plurality of passages in the movable member, and means for passing said dispensed oil to the filter.

35 10. In an oiling system as applied to internal combustion engines, an oil filter, means for supplying oil to the bearing parts of the engine, a camshaft, means associated with said camshaft serving as an oil dispensing means, and means including a duct in the crankcase for returning said dispensed oil to the oiling system through the filter.

40 11. In an oiling system as applied to internal combustion engines, an oil filter, means for supplying oil to the bearing parts of the engine, a camshaft, a passage in the camshaft positioned at a camshaft bearing and serving as an oil dispensing means, and means for returning said dispensed oil to the oiling system through the oil filter.

45 12. In an oiling system as applied to internal combustion engines, an oil filter, means

for supplying oil to the bearing parts of the engine, a camshaft, a passage in the camshaft serving as an oil dispensing means, and means including a duct in the crankcase for returning said dispensed oil to the oiling system through the oil filter.

50 13. In an oiling system as applied to internal combustion engines, an oil filter, means for supplying oil to the bearing parts of the engine, a camshaft, a plurality of passages in the camshaft positioned at a bearing and serving as an oil dispensing means, and means for returning said dispensed oil to the oiling system through the oil filter.

55 14. In an oiling system as applied to internal combustion engines, an oil filter, means for supplying oil to the bearing parts of the engine, a camshaft, a plurality of passages in the camshaft serving as an oil dispensing means, and a duct in the crankcase for returning said dispensed oil to the oiling system through the oil filter.

60 15. In an oiling system as applied to internal combustion engines, an oil filter, means for supplying oil to the bearing parts of the engine, a camshaft, oil dispensing means in the camshaft at a camshaft bearing, said dispensing means comprising a groove at the camshaft bearing, one or more passages in the camshaft, and a passage connecting the groove and first named passage or passages, and means for returning the oil to the oiling system through the oil filter.

65 16. In an oiling system as applied to internal combustion engines, an oil filter, means for supplying oil to the bearing parts of the engine, a camshaft, oil dispensing means in the camshaft at a camshaft bearing, and a duct in the crankcase for returning the oil to the oiling system through the oil filter, said dispensing means registering intermittently with said duct.

70 17. In an oiling system as applied to internal combustion engines, an oil filter, means for supplying oil to the bearing parts of the engine, a camshaft, oil dispensing means in the camshaft at a camshaft bearing comprising two passages at right angles to each other through the camshaft, and means for returning the oil to the oiling system through the oil filter, said passages registering intermittently with said last named means to supply a shot of oil for the filter.

75 18. In an oiling system as applied to internal combustion engines, an oil filter, means for supplying oil to the bearing parts of the engine, a camshaft, oil dispensing means in the camshaft at a camshaft bearing including a plurality of passages in the camshaft, and means including a duct in the crankcase for returning the oil to the oiling system through the oil filter, said passages registering intermittently with said duct to supply a shot of oil for the filter.

80 19. In a lubricating system for internal
